UNITED STATES PATENT OFFICE

WILLIAM T. HANNA, OF CINCINNATI, OHIO.

AUTOMATIC STOKER.

Application filed December 11, 1920. Serial No. 430,020.

REISSUED

To all whom it may concern:

Be it known that I, WILLIAM T. HANNA, a citizen of the United States of America, and resident of Cincinnati, in the county of 5 Hamilton and State of Ohio, have invented a new and useful Improvement in Automatic Stokers, of which the following is a specification.

An object of my invention is to provide a 10 compact and efficient stoker especially adaptable to locomotives, that may be readily mounted on a locomotive.

Another object is to provide a device of the type referred to and for the purpose 15 stated in which substantially all of the driving mechanisms are disposed below the floor of the engine cab.

These and other objects are attained by the means described herein and disclosed in 20 the accompanying drawing in which:—

Fig. 1 is an elevation taken on line 1—1 of Fig. 3, parts being broken away and showing a device embodying my invention, mounted on a locomotive.

25 Fig. 2 is a sectional view on line 2—2 of Fig. 1.

Fig. 3 is a side elevational view, looking to the right on Fig. 1, parts being broken away.

30 Fig. 4 is an enlarged sectional view on line 4—4 of Fig. 2.

Fig. 5 is an enlarged sectional view on line 5—5 of Fig. 4.

The stoker of my invention comprises a 35 housing A, which surrounds the usual firing opening, a fuel conduit a¹⁵, which enters the lower end of the housing, a feeder D which carries fuel to the fuel conduit from the tender E¹ and forces it upward in the conduit, and elevating and distributing mechanism in housing A. Housing A contains within it the elevating conveyors a³ and a⁴ to the lower ends of which conveyors the fuel is fed by the conveyors E and D. The 45 housing together with the elevating conveyors are adapted to be mounted about and adjacent to the door of the locomotive fire box. Housing A is preferably pear shaped having upwardly and outwardly diverging sides and is secured upon the boiler C of the locomotive C¹ above the cab floor c³ by any suitable means such as bolts a, and has a secondary firing opening a¹ in its rear wall a² and an aperture a²⁸ formed in the front wall a¹⁶ of the housing. The aperture a²⁸ and secondary firing opening a¹ are

substantially in horizontal alignment with the primary firing opening e in the boiler, which is located in alignment with the longitudinal centerline of the grate c². 60 Contained within the housing A and disposed between the rear wall a² and the forward wall a¹⁶ thereof are the elevating conveyors a³ and a⁴. The forward wall a¹⁶ of housing A engages and is mounted upon 65 the rear outer wall c¹ of the boiler C. The elevating conveyors comprise the tubes a⁵ and a⁶⁰ forming part of housing A and the spiral screws a⁶ and a⁶⁰ rotatably mounted therein. The spiral screws are driven by 70 any suitable means such as the driving mechanism B that is preferably disposed below the cab floor c³. The driving mechanism may be of any type adapted to impart rotatory motion. The drive mechanism B 75 has extending therefrom a drive shaft b, adapted to revolve the shaft a⁹ upon which is mounted the screw a⁶⁰. Shaft a⁹ drives the shaft a¹⁷ by means of the beveled gears a⁷ and a⁷⁰ mounted on the shafts a¹⁷ and a⁹ 80 respectively by means of the keys a¹⁸. The beveled gears a⁷ and a⁷⁰ are contained within the supplemental housing a⁸ formed at the base of the housing A and thru which the shafts a⁹ and a¹⁷ extend. The spiral 85 screws are mounted fixedly on the shafts a⁹ and a¹⁷ by means of the pins a¹⁹ whereby the shafts a⁹ and a¹⁷ and the screws a⁶ and a⁶⁰ are operated in unison from a common driving mechanism. The supplemental housing a⁸ forms a base or bottom for the tubes a⁵ and a⁶⁰ and is formed integral with the conduit a¹⁵. A plate a¹⁴ is secured to the base of the supplemental housing a⁸ and forms a closure for the chamber a¹⁹ within 95 which the gears a⁷ and a⁷⁰ are contained. The shaft a⁹ extends thru the plate a¹⁴ to a point without the housing A at which it is attached to drive shaft b of the drive mechanism B by means of a universal joint 100 b². An end bearing a²⁰ is mounted upon the plate a¹⁴ within the chamber a¹⁹ and serves as an abutment for shaft a¹⁷ and the gear mounted thereon. The upper ends of the tubes a⁵ and a⁶⁰ are enlarged and have 105 angular shoulders a²⁹ formed thereon. The inner and bottom edges a¹¹ of the shoulders a²⁹ extend over the adjustable distributing chutes a¹² and a¹²⁰ mounted on the rocking shafts a¹³ and a¹³⁰ which shafts are carried 110 by the housing A. The chutes are controlled by means of the arms a³⁰ and a³⁰⁰ having

2
sleeves rotatably mounted on shafts a^{13} and a^{130} . Lug plates a^{31} and a^{310} are carried by arms a^{30} and a^{300} and may be engaged by lugs formed on the handles a^{32} and a^{320} , said 5 handles having hubs mounted on the shafts a^{13} and a^{130} . When it is desired to render the chutes inoperative, the lugs are disengaged from the lug plates, wherefore when the handles are rotated, the chutes may be 10 swung clear of the shoulders a^{29} so as not to interfere with hand stoking thru the housing and the primary feeding opening. The chutes may be oscillated above their pivotal mountings by means of the controlling device A^1 , to the reciprocating shaft R of which, the arms a^{30} and a^{300} are pivotally connected by suitable links r and r^1 . The lug plates are provided with spaced slots a^{311} in which the handles may engage, as 15 shown in Fig. 5, whereby to transmit motion between the handles, and to vary the arcs thru which the chutes a^{12} and a^{120} may be oscillated. Further explanation of the chutes is deemed unnecessary as the action 20 thereof is fully explained in my copending application Serial Number 308,851 and need not therefore be more specifically described herein. The ways or bores formed in tubes a^5 and a^{50} , communicate adjacent their lower 25 ends with the conveyor D by means of the conduit a^{15} . A casing a^{21} is secured to the supplemental housing a^8 and extends below the cab floor c^3 and provides the lower terminus of the conduit a^{15} . A ball and socket 30 joint a^{22} connects the rear end of the casing a^{21} and the forward end of the casing d that surrounds the conveyor screw d^1 . 35

An observation door a^{24} is formed in the rear of the housing A immediately below the 40 opening a^1 such door opening into the tubes a^5 and a^{50} at their bases. A plate a^{25} is adapted to form a closure for the observation door. By means of the observation door, the operator can watch the fuel 45 fed to the furnace and can remove any slack or other non-combustible or deleterious material. Apertures a^{26} , see Fig. 4, are formed in the sides of the casing, adjoining the base of the tubes a^5 and a^{50} to facilitate 50 assemblage and to facilitate removing of any obstructions in the tubes. The plates a^{27} form closures for the apertures a^{26} .

The conveyor D comprises a tubular casing d within which is mounted a spiral screw 55 d^1 . The conveyor E comprises the tubular casing e mounted on the tender E^1 and which communicates with the supply of fuel in the tender in any manner common in the art and a spiral screw e^1 is revolvably and 60 centrally mounted within the tubular casing e in any manner well known in the art. The conveyors are disposed below the cab floor c^0 . The tubular member e is adapted to be connected with and to extend into the rear 65 end of the tubular casing d of the conveyor

D, in a manner well known in the art. The spiral screw d^1 is connected with the spiral screw e^1 by means of a universal joint d^3 . The spiral screw e^1 is driven by means of gears e^2 , mounted on the tender, one of said 70 gears e^2 being driven by drive shaft e^3 , which shaft is connected by universal joint e^4 to the driving shaft e^5 , which shaft is connected by a universal joint e^6 to the driving mechanism B . The second gear is 75 mounted on the shaft carrying the spiral screw e^1 .

Mounted between the housing A and the rear wall of the boiler C and extending thru the primary firing opening is the distributor plate f . Mounted adjacent and extending over the distributor plate f are a series of ejector nozzles f^1 adapted, together with the distributor plate, to feed the fuel evenly over the bed of the furnace which nozzles are 80 preferably of the type illustrated and explained in my copending application, Serial Number 377,226, and which therefore require no further explanation or description. The doors G are pivotally mounted on the 85 housing A and normally close the opening a^1 in the housing. The doors are provided at their upper ends with meshing gear segments, whereby when one of the doors is rotated about its pivotal mounting, the other 90 door is also rotated. Any suitable means such as a lever g^1 fastened to one of the doors may be employed to open and close the doors. The doors may be opened either 95 manually or automatically, as described in 100 my said copending application.

In operation the screws e^1 and d^1 carry the fuel from the conveyor D and force it thru the conduit a^{15} and into the tubes a^5 and a^{50} . The shaft a^0 is rotated by the drive 105 mechanism B whereby the spiral screws mounted within the tubes a^5 and a^{50} carry the fuel upward thru the tubes a^5 and a^{50} and push the fuel over the shoulders a^{20} whereupon the fuel falls upon the chutes 110 a^{12} and a^{120} and is guided by means of the chutes to the desired position above the distributor plate f and the ejector f^1 . As the fuel falls upon the ejector and the distributor plate, the fuel is carried by jets of air 115 or steam to various parts of the grate of the locomotive.

Should the stoker fail, the chutes may be swung to an inoperative position as heretofore described and the boiler can be fired 120 thru the aperture a^{28} in the housing and thru the firing openings in the boiler and housing.

As an auxiliary means adapted to cooperate with the conveyors E and D , in moving the fuel thru the conduit a^{15} , I provide a blast nozzle or series of nozzles h which extend into the conduit a^{15} , and by means of which a blast of air or steam may be introduced into the conduit a^{15} to assist in con- 125

veying the fuel upward thru the conduit and into the elevating conveyors in the housing A.

What I claim is:

5. 1. In a locomotive stoker the combination of a fire-box, having a firing opening located in alignment with its longitudinal axis, a housing embracing the firing opening, a distributing plate mounted adjacent in its forward wall registering with the primary firing opening, and having a secondary firing opening in its rear wall and in substantial alignment with the primary firing opening and the aperture, an elevating conveyor within the housing adapted to carry fuel from the base of the housing to points near the top thereof, a chute pivotally mounted within the housing adapted to direct fuel from the top of the conveyor thru the aperture in the housing and thru the primary firing opening, and means to feed fuel to the elevating conveyor. 70
10. 2. In a locomotive stoker the combination of a fire-box having a primary firing opening, of a housing having an aperture in its forward wall registering with the primary firing opening, a distributor plate extending into the primary firing opening, a chute mounted pivotally within the housing and projecting over the distributor plate, and means within the housing for feeding fuel to the chute. 75
15. 3. In a locomotive stoker the combination with a fire-box, having a primary firing opening, of a housing having an aperture in its forward wall registering with the primary firing opening, a distributor plate extending into the primary firing opening, a chute mounted pivotally within the housing and projecting over the distributor plate, and means within the housing for feeding fuel to the chute. 80
20. 4. In a locomotive stoker the combination with a fire-box, having a primary firing opening, of a housing having an aperture in its forward wall registering with the primary firing opening, a distributor plate extending into the primary firing opening, a chute mounted pivotally within the housing and projecting over the distributor plate, and means within the housing for feeding fuel to the chute. 85
25. 5. In a locomotive stoker the combination with a fire-box, having a primary firing opening, of a housing having an aperture in its forward wall registering with the primary firing opening, a distributor plate extending into the primary firing opening, a chute mounted pivotally within the housing and projecting over the distributor plate, and means within the housing for feeding fuel to the chute and means to supply fuel to the fuel feeding means. 90
30. 6. In a locomotive stoker the combination with a fire-box, having a primary firing opening, of a housing having an aperture in its forward wall registering with the primary firing opening, elevating conveyor within the housing adapted to carry fuel from the base of the housing to points near the top thereof, and a chute pivotally mounted within the housing adapted to direct fuel from the top of the conveyor thru the aperture in the housing and thru the primary firing opening. 95
35. 7. In a locomotive stoker the combination of a fire-box having a primary firing opening, of a housing having an aperture in its forward wall registering with the primary firing opening, and having a secondary firing opening in its rear wall and in substantial alignment with the primary firing opening and the aperture, an elevating conveyor within the housing adapted to carry fuel from the base of the housing to points near the top thereof, a chute pivotally mounted within the housing adapted to direct fuel from the top of the conveyor thru the aperture in the housing and thru the primary firing opening, and means to feed fuel to the elevating conveyor. 100
40. 8. In a stoker mechanism, the combination of a fire-box having a firing opening in its wall, a housing mounted adjacent to and extending about the firing opening, an ejector mounted adjacent the firing opening and adapted to direct fuel into the fire box, a chute mounted pivotally within the housing adapted to direct fuel to the ejector and means within the housing for feeding fuel to the chute. 105
45. 9. In a stoker mechanism the combination of a fire-box having a firing opening in its wall, a housing mounted adjacent to and extending about the firing opening, a distributor plate adjacent the firing opening, an ejector adjacent the distributor plate adapted to direct fuel into the fire box, a chute mounted pivotally within the housing adapted to direct fuel to the ejector and distributor plate, and means within the housing for feeding fuel to the chute. 110
50. 10. In a stoker mechanism the combination of a housing having a chamber, adapted to be mounted adjacent to and to embrace a firing opening, the housing having upwardly extending ways formed in it, the ways extending above the firing opening and communicating at their tops with the chamber, pivotally mounted chutes within the chamber projecting below the tops of the ways, a supplemental housing below the first mentioned housing having a fuel conduit communicating with the lower ends of the ways; a revoluble drive shaft extending thru the supplemental housing into one of the ways, a driven shaft extending into the supplemental housing and into a second one of the ways, means within the supplemental housing for transmitting motion from the drive shaft to the driven shaft, and spiral screws 115
55. 11. In a locomotive stoker the combination with a fire-box, having a primary firing opening, of a housing having an aperture in its forward wall registering with the primary firing opening, and having a secondary firing opening in its rear wall and in substantial alignment with the primary firing opening and the aperture, an elevating conveyor within the housing adapted to carry fuel from the base of the housing to points near the top thereof, and a chute pivotally mounted within the housing adapted to direct fuel from the top of the conveyor thru the aperture in the housing and thru the primary firing opening. 120
60. 12. In a locomotive stoker the combination with a fire-box, having a primary firing opening, of a housing having an aperture in its forward wall registering with the primary firing opening, and having a secondary firing opening in its rear wall and in substantial alignment with the primary firing opening and the aperture, an elevating conveyor within the housing adapted to carry fuel from the base of the housing to points near the top thereof, and a chute pivotally mounted within the housing adapted to direct fuel from the top of the conveyor thru the aperture in the housing and thru the primary firing opening. 125
65. 13. In a locomotive stoker the combination with a fire-box, having a primary firing opening, of a housing having an aperture in its forward wall registering with the primary firing opening, and having a secondary firing opening in its rear wall and in substantial alignment with the primary firing opening and the aperture, an elevating conveyor within the housing adapted to carry fuel from the base of the housing to points near the top thereof, and a chute pivotally mounted within the housing adapted to direct fuel from the top of the conveyor thru the aperture in the housing and thru the primary firing opening. 130

within the ways mounted upon the drive and driven shafts.

11. In a stoker mechanism the combination of a housing having a chamber therein, 5 adapted to be mounted adjacent to and to embrace a firing opening, and having upwardly extending ways formed in it, the ways extending above such firing opening and communicating at their tops with the 10 chamber, pivotally mounted chutes within the housing projecting below the tops of the ways, a supplemental housing forming a base for the first mentioned housing, having a chamber formed within it, the supplemental 15 housing having a fuel conduit formed in it, the fuel conduit communicating with the lower ends of the ways, a revolute drive shaft extending thru the walls of the supplemental housing and the chamber 20 therein, and projecting into one of the ways, a driven shaft extending thru a wall of the supplemental housing projecting into the supplemental housing chamber and into a second one of the ways, means within the 25 last mentioned chamber adapted to transmit motion from the drive shaft to the driven shaft, and means to rotate the drive shaft.

12. In a locomotive stoker the combination of a fire-box, having a firing opening 30 located in alignment with its longitudinal axis, a housing embracing the firing opening, a distributing plate mounted adjacent the housing and extending into the firing opening, a pivotally mounted chute within 35 the housing and adapted to direct fuel to the distributing plate, means within the housing for feeding fuel to the chute, and means to oscillate the chute about its pivotal mounting.

13. In a locomotive stoker the combination with a firebox having a firing opening, of a housing having an aperture in its forward wall registering with the firing opening, a distributor plate extending into the 45 firing opening, a pivotally mounted chute within the housing and projecting over the distributor plate, means within the housing for feeding fuel to the chute, and means to oscillate the chute about its pivotal mounting.

14. In a locomotive stoker the combination with a firebox, having a firing opening, of a housing having an aperture in its forward wall registering with the firing opening, a distributor plate extending into the 55

firing opening, a pivotally mounted chute within the housing and projecting over the distributor plate, means within the housing for feeding fuel to the chute, means to supply fuel to the fuel feeding means, and 60 means to oscillate the chute about its pivotal mounting.

15. In a stoker mechanism the combination of a furnace having a firing opening in its wall, a housing mounted upon the exterior of the furnace and embracing the firing opening, means associated with the furnace and the housing for feeding fuel to the furnace by way of the firing opening therein, a pivotally mounted chute within the housing 65 adapted to direct fuel to the feeding means, means within the housing for conveying fuel to the chute, and means to oscillate the chute about its pivotal mounting.

16. In a locomotive stoker the combination of a fire-box having a primary firing opening, a housing embracing the firing opening and having an aperture and a secondary firing opening therein in alignment with the primary opening, a door for the 80 secondary opening, a distributor plate extending into the primary firing opening, a pivotally mounted chute within the housing adapted to direct fuel to the distributor plate, means within the housing for feeding 85 fuel to the chute, and means to oscillate the chute about its pivotal mounting.

17. In a stoker mechanism the combination of a housing having a chamber, adapted to be mounted adjacent to and to embrace a 90 firing opening, the housing having upwardly extending ways therein communicating at their tops with the chamber, pivotally mounted chutes within the chamber projecting below the tops of the ways, a supplemental housing having a fuel conduit communicating with the lower ends of the ways, a revolute drive shaft extending thru the supplemental housing into one of the ways, a driven shaft extending into the supplemental housing and into a second one of the ways, means within the supplemental housing for transmitting motion from the drive shaft to the driven shaft, and spiral screws 95 within the ways mounted upon the drive and driven shafts.

In testimony whereof, I have hereunto subscribed my name this ninth day of December, 1920.

WILLIAM T. HANNA.
